WELL CLEANER

Claude C. Taylor, Whittier, Calif.

Application April 22, 1936, Serial No. 75,712

13 Claims. (Cl. 166—20)

This invention relates to well cleaners and specifically contemplates means for washing the walls and clogged perforations of well casing-screens by subjecting adjacent zones of the screen to the simultaneous application of, respectively, fluid pressure and suction and thereby to also disintegrate debris accumulated at the mouths of oil-producing fissures of the surrounding sands.

The separate application of suction or pressure within the well screen is in many instances insufficient to effectively remove the debris which accumulates in the well bore around the casing. Suction directed thereto is usually relieved by the ingress of well fluid through only the most easily cleaned perforations without removing obstructions from the others. As the bulk of the clogging accretions is outside of the screen rather than in the perforations themselves, having converged by the flow of oil fluid toward the well stimulated by pump suction from within the pipe or rock pressure around the well, further suction often only tends to wedge the detritus more firmly together.

While pressure fluid forcibly discharged from within the casing may both dislodge and disintegrate the accumulations adjacent the casing perforations, it provides no means for permanently removing the constituents thereof, which can later reunite in and around the perforations as prior to the operation.

It is therefore highly important in such well cleaning devices that both pressure and suction be applied to the screen to, first, disintegrate the viscid matter; second, wash the walls of both the casing and bore of the hole; and third, to draw the same into the screen before the reaccumulation thereof, to facilitate its subsequent removal from the well.

It is a principal object of this invention to provide a well cleaner comprising a plurality of swabs to slidably close the bore of the casing-screen, adapted for relative movement by the vertical reciprocation of a tubing, and thereby, simultaneously, create a zone of suction in the screen, and, preferably above and adjacent the zone of suction, an area of pressure, thus actuating a flow of oil fluid through a pre-determined set of perforations, downwardly between the casing wall and the well bore, and thence return through a lower set of perforations into the screen.

Another object is the provision of a device whereby a series of casing swabs may be relatively moved by reciprocation of a tubing string to alternately shorten and lengthen the zones between respective pairs of swabs a distance greater

than the stroke of the tubing string required for movement thereof.

Other objects will be apparent to those of skill in this art upon an examination of the following description read in the light of the accompanying drawings, in which—

Fig. 1 is a sectional view of my invention as operatively installed in a well casing;

Fig. 2 is an enlarged section of the gear mechanism employed to raise the middle packer on 10 the tubing;

Fig. 3 is a transverse fragmentary section taken on line 3—3 of Fig. 1;

Fig. 4 is a transverse sectional view on line 4—4 of Fig. 1;

Fig. 5 is a fragmentary sectional view of a modified portion of my invention installed in a well casing;

Fig. 6 is a sectional view of the modification of Fig. 5 taken at right angles thereto;

Fig. 7 is a transverse section on lines 7—7 of Fig. 5;

Fig. 8 is a fragmentary sectional view of a third embodiment of my invention;

Figs. 9 and 10 are transverse sections on correspondingly-numbered lines of Fig. 8.

Referring to the drawings in detail, the numerals of which indicate similar parts throughout the several views, 10 designates a section of casing screen, commonly assembled in a string of imperforate casing, and positioned opposite the oil-producing sands, into which oil fluid is adapted to flow through perforations 11 therein. A tubing string 12 within screen 10 is provided, having a short collar 13 secured to its lower end by a coupling 14. On the outer periphery of collar 13 slightly below the base of its upper thread, an annular shoulder 15 is formed against which a swab 16 is clamped by the lower edge of coupling 14. A tubing section 17 of a diameter smaller than tubing 12 is threaded to the lower end of collar 13. An expander 18 of slip mechanism, well known in the art, is slidably keyed on tubing 17 by a pair of longitudinal, diametrically-opposite feathers 19 integrally formed with the tubing, 40 to compel rotary motion of the tubing to rotate the expander but permitting relative vertical movement of the parts. The lower receding sides of expander 18 are provided with dovetail grooves into which slips 20 are keyed. A series of outwardly bowed springs 21 have their ends secured to upper and lower collars 22 and 23, respectively, which slidably encircle a sleeve 24 threaded to the lower end of expander 18. In the upper collar 22 a ring 25 is rotatably retained by well 50

- known means, to which ring slips 20 are pivotally attached by connecting arms 26. Springs 21 normally maintain the spaced relation of collars 22 and 23 and are adapted to expand against the 5 wall of the casing. A stud 27 mounted on and forming an integral part of sleeve 24 cooperates with a J-lock 28 of a design well known in the art, downwardly projecting from lower collar 23, to hold slips 20 at the base of the expander.
- 10 A gear race 29 (Fig. 2) threaded on the lower end of sleeve 24 has an inner lower rim 30 of a width substantially equal to the thickness of the sleeve, forming an upwardly-directed bearing 31. Between the lower edge of sleeve 24 and bearing 15 31 annular gear 32 is interposed, having a groove helically formed in its bore with which a helical gear tooth 33 formed on tubing 17 is adapted to mesh so as to compel rotation of the gear by vertical movement of the tubing, gear 32 being 20 restrained from following the reciprocatory motive of tubing 17 by the slip mechanism which mounts race 29, in which gear 32 operates, immovably with the casing wall as described.
- 25 A circular gear 34 around tubing 17 below race 29 is threaded to gear 32 so as to rotate therewith. Triple helical threads on the outer periphery of gear 34 mesh with the triple internal helical teeth 35 of a hollow mandrel 36 concentrically encircling gear 34.
- 30 A cylindrical guide 37 is threaded on race 29, into the bore of which mandrel 36 is adapted to telescope. A series of lugs 38 on the mandrel protrude into vertical slots 39 formed in guide 37 which permit vertical movement of the mandrel 35 but prevent its rotation with gear 34.
- 35 An upwardly-inclined swab 40 adapted to close the bore of the casing to pressure thereabove, is clamped between an annular shoulder 41 on the lower end of mandrel 36 by a collar 42 threaded on the mandrel. In the lower bore of the mandrel an annular shoulder 43 slidably engages tubing 40 17. A gland 44 threaded into the bore of the mandrel compresses packing 45 against shoulder 43 to prevent the dissipation of pressure created 45 between swabs 16 and 40 upon their movement together as will hereinafter be described in detail.
- 45 A lower diametrically-enlarged tubing section 46 is threaded on tubing 17, forming an upwardly-directed shoulder 47 for a purpose herein-after referred to. Near the top of tubing section 50 46 a downwardly-inclined swab 48 is secured by means similar to that connecting swab 16, which closes the bore of the casing to suction thereabove.
- 55 The zones around the tubing above swab 16 and below swab 48 are communicated by ports 49 and 50 through coupling 14 and tubing section 46, respectively, to prevent disturbance of the well fluid level during manipulation and positioning of the swabs.
- 60 The operation of the embodiment of my invention shown in Figs. 1-4 will now be briefly described: The slips 20 are locked at the base of expander 19 and the device lowered in the well. Fluid may pass into the tubing through port 50 and the level of fluid within the tubing maintained even with that outside thereof by communication through port 49. The device is lowered to position opposite the lower zone 70 of the oil producing sands. Tubing string 12 is then raised slightly and the slips released from J-lock 28 by rotation of the tubing in a manner well known in the art, after which the lowering of the tubing will cause the slips to grip the 75 casing, restraining the expander, sleeve and

elements threaded thereto from longitudinal movement relative to the casing, as well as to prevent rotation through guide 37 and lugs 38 of mandrel 36. Thus the continued lowering of the tubing will compel rotation of gear 32 and gear 34 which will elevate mandrel 36 and swab 40. Pressure will accordingly be created between swab 16, which is lowered on the tubing and swab 40. This pressure can only be relieved through perforations 11 of the casing. The force 10 of the discharging oil fluid through the perforations will disintegrate the debris adjacent perforations 11 and fissures of the oil sands. Swab 48 will also be lowered with the tubing, causing a zone of suction to form between the two lower 15 swabs which will be relieved by the passage therein of the debris dissociated by the pressure created in the adjacent part of the tool. On the upward stroke of the tubing the middle swab 40 will be lowered and the upper and lower swabs 20 16 and 48, respectively, elevated, causing suction in the upper packed-off zone which is relieved by the passage of fluid downwardly around swab 16. A port 51 in tubing 17 having a valve 52 adapted to open to suction between swabs 16 and 40, is provided, through which fluid from within the tubing may enter the zone between the upper swabs when the tubing is raised. The weight of the mandrel and swab 40 will facilitate its return to its lower position, 30 which is limited by abutment of the lower edge of mandrel 36 against shoulder 47 on tubing 46.

35 The oil fluid and debris drawn through perforations 11 of the casing on the downstroke of the tubing passes on the reverse stroke through a port 53 in tubing 46 located above the lower swab. To prevent the passage of this debris upwardly through the bore of the tubing and thence through port 51 into the pressure zone, a partition 54 is provided which divides the bore of 40 the tubing from above port 53 to below port 50. A valve 55, of any well known type, in the bore through tubing 46 below partition 54 prevents return of the debris to the zone between the packers on the downward or suction stroke of 45 the lower swab.

50 Referring particularly to the embodiment of my invention illustrated in Fig. 5; Sleeve 24 which may be identical with the correspondingly-numbered sleeve illustrated in Figs. 1-4, having slip mechanism associated therewith as described above, has threaded to its lower end a cylinder 56. Tubing section 17a threaded to the end of the tubing 12 (not shown) extends concentrically through the bore of cylinder 56. Telescoping over cylinder 56 a mandrel 57 is provided, on the lower end of which swab 40 is mounted in the manner above described. A pair of oppositely-disposed lugs 58 secured in the bore of mandrel 57 protrude through vertical slots 59 in cylinder 56. At the opposite end of each of said slots in the bore of cylinder 56, pulleys 60 are pivoted by well known means.

55 A pair of continuous cables 61 pass over respective vertically aligned pulleys 60. One stretch of each cable is secured by well known means to a lug 62 located in vertical alignment with respective pulleys on tubing 17a. The other stretch of each cable is attached to its aligned lug 58 extending from the mandrel through its respective slot 59. Thus, as the tubing is lowered, cables 61 will be actuated by the lowering of lugs 52 to raise lugs 58 and mandrel 57 with swab 40 attached thereto. In other particulars 60

this modification (Fig. 5) is identical with the embodiment above described in detail.

The device illustrated in Figs. 8, 9 and 10 is a modified form of reciprocating means for the lower packer in which a cylinder 63 is threaded to the lower end of sleeve 24. Through the bore of cylinder 63 tubing 17b extends as in the above described embodiments. The lower bore of cylinder 63 is built up on opposite sides as at 64 to fill the annular area between the cylinder and tubing. The portions 64 of the cylinder are diametrically slotted at 65, which slots are intersected by parallel holes 66. Pinions 67 are rotatably retained in slots 65 by pins 68 inserted in holes 66. The bodies of pinions 67 have a diameter approximately equal to the width of individual portions 64 of the cylinder so as to permit the teeth thereof to extend outwardly from opposite sides. A mandrel 69 telescopes over cylinder 63 and is provided with gear racks 70 oppositely disposed on the inner wall thereof so as to mesh with respective pinions 67. Tubing 17b is likewise provided with integral gear racks 71, the teeth of which mesh with the teeth of respective pinions 67 at the opposite side thereof from their contact with racks 70 of mandrel 69. The outer wall 63 is longitudinally cut away at opposite sides to provide tracks 72 in which the teeth of mandrel 69 are adapted to reciprocate and accordingly prevent misalignment of the racks 70 with respect to the pinions. Thus, the lowering or raising of the tubing will rotate pinions 67, causing vertical movement of the mandrel in a direction opposite to that of the tubing.

From the foregoing description and accompanying drawings, it will be obvious to those of skill in this art that numerous changes may be made in size, arrangement, proportion and design of the various parts; that other than reciprocatory motion may be utilized by the drill pipe to compel relative movement of the swabs; that any by-pass well known in the art may be substituted for the type disclosed; that other means actuated by the tubing for moving the swabs in opposite directions may be employed, all without departing from the spirit of my invention as defined in the appended claims.

What I claim and desire to cover by Letters Patent is:

1. In a well cleaner, a casing, a tubing string within said casing, a pair of swabs encircling the tubing, and means to simultaneously move both of said swabs in opposite directions with respect to the casing by movement of the tubing.

2. In a well cleaner, a casing, a tubing string within said casing, a pair of swabs encircling the tubing, each adapted to close the annular area between the tubing and casing, means to simultaneously reciprocate said swabs in opposite directions through the bore of the casing to create suction between the swabs upon their separation, and means within the casing to relieve pressure therebetween during the opposite stroke of said swabs.

3. In a well cleaner, a casing, a tubing string within said casing, a pair of swabs encircling the tubing, each adapted to close the annular area between the tubing and casing, means to simultaneously reciprocate said swabs in opposite directions through the bore of the casing to create pressure between the swabs by their movement toward each other, and means within the casing to relieve suction therebetween during the opposite stroke of said swabs.

4. In a well casing cleaner, a tubing string, a

pair of swabs encircling said tubing string, means to simultaneously reciprocate the swabs in opposite directions with respect to the casing by movement of the tubing, and means to communicate the area below the lowermost swab with the zone between the swabs. 5

5. In a well cleaner, a well casing, a tubing string within said casing, a swab secured to said tubing and movable therewith, a second swab encircling said tubing, and means actuated by movement of the tubing to move said second swab with respect to the casing in a direction opposite to that of the first swab. 10

6. In a well cleaner, a well casing, a tubing string within said casing, a plurality of swabs encircling the tubing, and means actuated by movement of the tubing to reciprocate each of said swabs with respect to the casing so as to cause separation of one pair and convergence of another pair of said swabs. 15

7. In a well cleaner, a casing string, a tubing string within said casing string, a pair of swabs secured to said tubing adapted to close the annular area between the tubing and said casing, a third swab slidably encircling said tubing between said first-mentioned swabs, and means actuated by movement of the tubing to cause movement of said third swab with respect to the casing in a direction opposite to the movement of said tubing. 20

8. In a well cleaner, a casing, a tubing string within said casing, a pair of swabs encircling said tubing, means to connect one of said swabs with the tubing to cause its reciprocation by movement of the tubing, a gear, means to support said gear in the casing, means to rotate said gear by movement of the tubing, and means actuated by said gear to cause reciprocation of the other of said swabs. 25

9. In a well cleaner, a casing, a tubing string within said casing, a pair of swabs encircling said tubing, means to connect one of said swabs with the tubing to cause its reciprocation by movement of the tubing, a pulley, means to support said pulley in the casing, a cable threaded through said pulley connecting said tubing with the other of said swabs so as to cause reciprocation of said last-mentioned swab by reciprocation of the tubing. 30

10. In a well cleaner, a well casing, a tubing string within said casing, a plurality of packers connected to said tubing string so as to be raised and lowered in the well with said tubing string, said packers forming a pair of confined zones therebetween, means actuated by movement of said tubing string to cause movement of one of said packers with respect to the well casing, in a direction opposite to said movement of the tubing string and enlarge and contract respective confined zones. 40

11. In a well cleaner, a well casing, a tubing string within said casing, a pair of packers connected to said tubing string so as to be raised and lowered in the well with said tubing string, said packers forming a confined zone therebetween, means actuated by movement of said tubing to move one of said packers with respect to the well casing in a direction opposite to the direction of said movement of said tubing string to cause alternate enlargement and contraction of the zone 45 between said packers. 50

12. In a well cleaner, a well casing, a tubing string within said casing, a pair of packers connected to said tubing string so as to be raised and lowered in the well with said tubing string, said 55

packers forming a confined zone therebetween, means actuated by movement of said tubing to move one of said packers with respect to the well casing in a direction opposite to the direction of said movement of said tubing string to cause alternate enlargement and contraction of the zone between said packers, and valve means to relieve suction and preserve pressure caused by movement of said packers.

13. In a well cleaner, a well casing, a tubing string within said casing, a pair of packers connected to said tubing string so as to be raised

and lowered in the well with said tubing string, said packers forming a confined zone therebetween, means actuated by movement of said tubing to move one of said packers with respect to the well casing in a direction opposite to the direction of said movement of said tubing string to cause alternate enlargement and contraction of the zone between said packers, and valve means to relieve pressure and preserve suction caused by movement of said packers.
